UNITED STATES PATENT OFFICE.

LESTER C. GAMMON AND DOCTOR D. BARNES, OF SANDPOINT, IDAHO.

DILATOR FOR FILES OR HEMORRHOIDS.

Application filed July 27, 1926. Serial No. 125,254.

This invention relates to surgical implements and particularly to rectal dilators.

Piles or hemorrhoids are tumors upon the walls of the rectum and about the anus and this is caused by a diseased condition of the veins and arteries of the lower bowels and tumors form from the size of grains of rice to the size of large walnuts. If these are neglected the tumors will not return to their places and finally disappear.

The general object of the present invention is to provide a dilator which may be inserted in the rectum from time to time and expanded to thus cause a pressure to bear upon the veins and cause the blood which collects in these sacs or tumors to be forced into circulation.

A further object is to provide a device of this character which may be used with very little pain and which from day to day may be used to dilate the rectum more and more and with greater pressure until the piles disappear and a still further object is to provide means whereby the dilator may be held for any desired length of time in its expanded condition.

Our invention is illustrated in the accompanying drawings wherein:—

Figure 1 is an elevation of an instrument constructed in accordance with our invention, the instrument being closed;

Figure 2 is a like view to Figure 1 but showing the instrument expanded, the rubber envelope being in section;

Figure 3 is a section on the line 3—3 of Figure 1.

Referring to these drawings it will be seen that the dilator comprises two handles 10 and 11 pivoted to each other at 12. One of the handles is provided with a shackle or ring 13 and the other with a series of teeth 14 with which the ring or shackle is adapted to engage. The extremities of the handles beyond the pivotal point 12 are extended in the form of outwardly divergent rods or shanks 15 and mounted upon these shanks is a rubber sheath 16. This sheath is made of one single piece of rubber approximately semi-circular in cross section which is bent into an approximate U-form and the shanks 15 are inserted in the ends of this U-shaped sheath. The bight portion of the sheath is somewhat notched at 17 so as to permit the

bending of the sheath as illustrated and as the handles are forced toward each other 55 the sheath will be caused to expand from the position shown in Figure 1, to the position shown in Figure 2.

Disposed over this sheath 16 is a thin rubber casing 18 which extends down to the lower end of the sheath and which is readily expanded or contracted. This rubber envelope fits around the rounded outer edges of the sheath and extends across between the legs of the sheath so as to provide a continuous outer surface for that portion of the instrument which is to be inserted into the rectum.

In the use of this device, the rectum should be dilated from day to day as much as possible without pain and every day the rectum should be dilated with greater and greater pressure until the dilator is open to its limit.

Of course this principle of the dilation of the rectum has been used before for the cure 75 of hemorrhoids but in all cases known to us a plurality of or a set of dilators have been used of different sizes which must be forced into the rectum and it is impossible to secure the very slight increase in dilation day after 80 day as is possible with our construction.

It will be seen that the instrument is very simple, can be readily used by anyone, and that it operates in a natural but thoroughly effective manner.

We claim:—

1. A dilator of the character described comprising handles pivoted to each other, a U-shaped dilating element of yielding material mounted upon the extremities of 90 the handles and dilated thereby, and an envelope of thin rubber extending over the U-shaped element and enclosing the same.

2. An instrument of the character described comprising handles pivoted to each other and having shanks projecting therefrom, a U-shaped member of rubber mounted upon said shanks, the member having an outer rounded edge surface and being adapted to be dilated by the compression of the 100 handles toward each other, and an envelope of thin soft elastic rubber extending over the U-shaped member.

3. An instrument of the character described comprising handles pivoted to each 105 other and having shanks extending there-

from, means locking the handles in various adjusted positions with relation to each other, and an approximately U-shaped member of rubber into the ends of which the handle shanks are inserted, the rubber member being adapted to be expanded by the compression of the handles, and an envelope of thin

rubber surrounding the U-shaped member and enclosing the same and expandible with the U-shaped member.

In testimony whereof we hereunto affix our signatures.

LESTER C. GAMMON.
DOCTOR D. BARNES.
